PERCUSSIVE TOOL APPLIANCE

Walter H. Moorhead, South Euclid, Ohio

Application September 27, 1946, Serial No. 699,912

5 Claims. (Cl. 74—56)

1

My invention pertains to a percussion tool and more particularly to an appliance for rotating and for intermittently reciprocating in an axial direction, a tool carried thereby.

I have satisfied myself that my relatively somewhat modified models perform in an improved manner, especially in small and light sizes suitable for convenient manipulation in their entirety and carrying cemented-carbide tools—provided speed of rotation and rapidity, force and distance of axial strokes have been most effectively correlated as empirically determined. An attainment of that desideratum has accordingly constituted my primary object. Minor objects have been a design which will be duly economical of manufacture and of operation, readily assembled, reliable and durable in use (with or without an optional adjustment feature) and adapted for successful performance for longer periods of time without tool regrinding or replacement.

Adverting to the drawing:

Figure 1 is mainly an axial or longitudinal section of an appliance embodying the principles of my invention.

Figure 2 is a radial section on line 2—2 of Figure 1, looking in the direction of the indicating arrows.

Figure 3 is a view corresponding to Figure 1 of a modified form of my origination.

Figure 4 is a radial section on line 4—4 of Figure 3 viewed as directed by the section-line arrows.

A tubular housing 1 fixedly encloses, consequent to the common expedient of a pressed or shrunk fit therebetween, (or slidably encloses if in splined connection) a thicker tubular member 2 which occupies only a middle section of the housing. One end face of the tubular member, cam cylinder or hammer 2 is fashioned, as exemplified, as a double-action cam comprising semi-annular convolute-sections of a helix, marked by the numerals 3 and 4 respectively and further comprising, each, an abrupt shoulder defined by a surface in a near-axial plane. Such shoulders 5 and 6 are diametrically opposite as may be observed in Figure 2. While I have experimentally come to prefer a double cam, a single or other multiple circumferential arrangement are alike feasible and have been manufactured and used. At its end which carries the cam, the interior tube 2 is provided with a bore 7 adapted to serve as one bearing for a central shaft 8. At its opposite end the tubular member 2 is formed with a comparatively larger bore 9,

2

to provide, in the radial plane where the bores 7 and 9 communicate with each other, an annular shoulder 10 serving as an abutment for one end of a compression, coil spring which envelops the shaft 8. An anti-friction bearing 12 on the shaft 8 abuts the other end of the spring 11 and the spring may be maintained in compression by a slotted, spring-clip 13 which is cheaper and more expeditious of attachment or removal than would be a nut cooperating with a threaded section of the shaft. Beyond the clip 13, the shaft is shown to be of slightly reduced size for connection with a common clutch provided on flexible driving members. The other end of the shaft 8 may, for instance, be integrally formed as a tool chuck 15 comprising the conventional set-screw 16 for clamping the shank of any chosen tool (not shown) and also including an enlargement 17 fitted within the housing 1. Eccentrically, the interior end of the enlargement 17 is supplied with a tapped hole 18 extending parallel with the axis and adjustably occupied by a threaded member 19 terminating as a projecting finger 20, the end surface of which is maintained in contact with the cam by the action of the spring 11 whereby, twice during each rotation of the shaft 8, it successively travels along one or the other of the two shoulders 5 and 6 thereby furnishing an adjustable control for wear during the release function or axial throw of the cam and of the shaft whereby to deliver a forward impulse to chuck and the tool.

The form hitherto described causes the handle-serving housing, when the appliance is in power-driven operation, to impart negligible hand tremors consequent to its reciprocation along with the tool. In the modified form next to be differentiated, a simple arrangement eliminates, not the slight and endurable vibration, but the positive reciprocation of the housing which is to be grasped by the hand. In the modification of Figure 3, the housing 21 may be exteriorly supplied with knurling (not shown, because long a common expedient to insure a firmer grip), but is definitely formed with an interior channel 22 extending parallel with the axis. The cam-bearing tube 23 is similarly formed with a complementary and registering channel 24. A key 25 occupies sections of said channels and while insuring the relative movement in an axial direction as between the tube 23 and the housing 21 whereby to be somewhat more comfortable, involves an added cost of manufacture.

Upon future consideration, it is to be realized that the scope of my invention, as defined by the

claims, comprehends equivalent constructions involving the same principle of operation and that the showing of the drawings and the specific description thereof are intended merely to exemplify a plurality of mechanical embodiments and arrangements.

For instance, the inner tube 2 or hammer might turn with the shaft and the cam-engaging finger be not rotatable whereby to achieve an equivalent mere reversal. Nor need the cam be on an end of the inner tube 2, because, though more complicated and expensive, it might be between its ends and the shaft carry the finger at a suitable place so as to ride thereover.

I claim:

1. In an appliance of the character described, the combination of a housing, a cam cylinder locked against turning movement interiorly thereof, a shaft mounted in said cylinder for both turning and axial movement relatively thereto, a driving connection for rotating said shaft, a coil spring within said cylinder and around said shaft for actuating the latter axially and means comprising a cam for controlling the axial movement of said shaft, said cam being formed with an abrupt, axially aligned shoulder surface adapted suddenly to permit the axial travel of said shaft in one direction in response to the action of said spring.

2. In combination, a hollow handle, an anti-friction bearing therein, a cylinder secured against turning movement therein and provided with axial bores of different diameter at its opposite ends respectively, one end of said cylinder being fashioned as an arcuate cam, a structure comprising a chuck and rotatably mounted in said cylinder and with one end in apposition to one end of said cylinder and carrying a projection adapted to engage and to travel around said cam, said structure further comprising a shaft mounted near one of its ends in said cylinder and near its other end in said bearing and a compression spring around said shaft and with its ends abutting an end of said cylinder and said bearing respectively.

3. In combination, a tubular structure having ends of varying thickness, the end of greater thickness being fashioned as an annular cam, another structure rotatably mounted in said tubular structure and having a chuck-forming end,

an axially adjustable wear-finger mounted on said chuck and adapted to cooperate with said cam whereby to permit the release throw of said rotatable structure, the latter including a shaft, a compression spring around said shaft and within said tubular structure and means for maintaining said spring in compression.

4. In combination, a housing, a shaft rotatably and reciprocably mounted in said housing and projecting from both ends thereof, a cam structure carried internally by said housing, the latter being also formed with an annular shoulder, a cam-engaging finger eccentrically carried by one end of said shaft, a coil spring around a part of said shaft and abutting said shoulder and means for holding said spring in compression, said cam structure comprising a plurality of circumferentially spaced crests terminating at planes extending in the same general direction as the axis

20 to define abrupt shoulders whereby successively to deliver sudden impacts during each rotation.

5. In combination, a composite housing, a cylinder reciprocable in said housing and including a cam surface, a shaft mounted in one end of said cylinder for rotatable and axially slidable movement, a coil spring around said shaft and occupying the other end of said cylinder for urging the latter axially and a structure adjustably carried by said shaft and adapted to engage the cam surface on said cylinder successively to retract said shaft against the action of said spring.

WALTER H. MOORHEAD.
